INVENTOR.

Seale Howard Ellis,
BY
Henry D. Williams
ATTORNEY

UNITED STATES PATENT OFFICE.

SEELE HOWARD ELLIS, OF BROOKLYN, NEW YORK, ASSIGNOR TO HUGH L. FOX, OF NEW YORK, N. Y.

CLAMP.

SPECIFICATION forming part of Letters Patent No. 710,049, dated September 30, 1902.

Application filed January 27, 1902. Serial No. 91,369. (No model.)

To all whom it may concern:

Be it known that I, SEELE HOWARD ELLIS, a citizen of the United States, residing in the borough of Brooklyn, in the county of Kings, 5 city of New York, and State of New York, have invented certain new and useful Improvements in Clamps, of which the following is a specification, reference being had therein to the accompanying drawings.

10 This invention relates to clamps, and a clamp embodying my invention is particularly adapted for clamping heavy parts upon a tubular support—as, for example, an engine or motor upon a bicycle-frame.

15 My invention has for its object to provide means for exerting a very considerable clamping pressure upon a tubular support, sufficient to permit the clamp to sustain a heavy weight and sharp concussions and vibrations without distortion or collapse of the tubular support.

20 I will now describe the clamp embodying my invention illustrated in the accompanying drawings and will thereafter point out my 25 invention in claims.

Figure 1 is a side elevation of a clamp embodying my invention, showing the same clamped upon a tubular cylindrical support. Fig. 2 is a vertical central section of the same.

30 Fig. 3 is a plan of the clamp with the support in section.

The tubular support 1 may be any part of the frame of a bicycle or railway-inspection car or other structure in which tubular construction is employed.

35 The part of the clamp which is in actual contact with the support comprises a longitudinally-divided sleeve of considerable length and shaped to conform to the support, so that 40 when tightly clamped upon the support this sleeve distributes the clamping pressure over a very considerable surface and, in fact, stiffens and strengthens the tubular support. In the construction shown the longitudinal 45 sleeve is divided into two nearly semicylindrical parts 2 and 3. One of the parts of the sleeve—the part 2—carries the attaching means for engagement with the device to be supported, such attaching means comprising

50 a cross-bar 4 and lugs 5, the cross-bar 4 being brazed or otherwise secured to or formed

upon the part sleeve 2 and further held thereto by braces 6, extending from the part sleeve to the cross-bar, and the cross-bar being located medially of the length of the sleeve. 55

The two part sleeves are clamped together by clamping-yokes, two clamping-yokes being shown, each located between the medial cross-bar or attaching means and an end of the sleeve. Each clamping-yoke comprises 60 a band 7, fitting upon one of the part sleeves, as shown fitted upon the part sleeve 2, and terminating at each end in a screw-threaded stem 8, the band as a whole being U-shaped. These bands coöperate with caps 9, with 65 which the screw-threaded stems engage by means of nuts 10, each cap bearing upon the part sleeve opposite to the part upon which its corresponding band 7 bears, and each cap having a flat bearing-surface and having an 70 angular flange conforming at its edges to the cylindrical surface of the part sleeve.

This clamping device is of simple construction and highly effective in operation. The bands 7 and caps 9 distribute their clamping 75 pressure over a considerable surface of the part sleeves and the part sleeves distribute their pressure over their full length. Each of the parts of the clamp coöperates with the other parts to stiffen and strengthen the 80 structure as a whole.

It is obvious that modifications may be made in the construction above particularly described within the spirit and scope of my 85 invention.

What I claim as my invention, and desire to secure by Letters Patent, is—

1. A clamp comprising an elongated sleeve divided longitudinally into parts, a plurality of clamping-yokes at different points along 90 the length of such sleeve and bearing upon such sleeve to clamp the parts thereof upon a support, and attaching means for engagement with the device to be supported, such attaching means being carried by one of the 95 parts of the sleeve.

2. A clamp comprising an elongated sleeve divided longitudinally into two parts, a plurality of clamping-yokes each having a band bearing upon one of such parts and a cap engaging with such band and bearing upon the other of such parts, and lugs for attachment 100

to the device to be supported or carried by one of the parts of the sleeve.

3. A clamp comprising an elongated sleeve divided longitudinally into two parts, a cross-
5 bar and lugs for attachment to the part to be supported medially carried by one of the parts of the sleeve, two clamping-yokes, one at each side of the attaching-lugs and between the attaching-lugs and the end of the sleeve, each
10 clamping-yoke having a band bearing upon one of the parts of the sleeve and a cap engaging with the band and bearing upon the other part of the sleeve.

4. A clamp comprising an elongated sleeve
15 divided longitudinally into parts, a plurality of clamping-yokes each comprising a U-shaped band having a bearing-surface upon such sleeve conforming thereto and also comprising a cap engaging with such band and
20 bearing upon the sleeve oppositely to the band, and attaching means for engagement

with the device to be supported, such attaching means being carried by one of the parts of the sleeve.

5. In a clamp, the combination of the part
sleeves 2 and 3, the cross-bar 4 and lugs 5 secured to the part sleeve 2, the braces 6 between the cross-bar and part sleeve, and the clamping-yokes each comprising the U-shaped band 7 having a bearing-surface upon
25 the sleeve conforming thereto and also comprising a cap 9 bearing upon the sleeve oppositely to the band, each U-shaped band 7 having ends engaged by clamping means with the cap of the corresponding yoke, substantially
30 as set forth.

In testimony whereof I have affixed my signature in presence of two witnesses.

SEELE HOWARD ELLIS.

Witnesses:

HENRY D. WILLIAMS,
HERBERT H. GIBBS.
